UNITED STATES PATENT OFFICE.

EDUARD UNVERRICHT, OF HAMBURG, GERMANY, ASSIGNOR TO DR. PAUL DE CHAPEAURCOUGE, OF HAMBURG, GERMANY.

CIRCUIT-CHANGER.

1,074,911.

Specification of Letters Patent.

Patented Oct. 7, 1913.

Application filed May 23, 1911. Serial No. 629,002.

To all whom it may concern:

Be it known that I, EDUARD UNVERRICHT, a citizen of the Hanse town of Hamburg, Germany, and residing at Hamburg, Germany, have invented a new and useful Circuit-Changer, of which the following is a specification.

This invention relates to a circuit changer of novel construction, which is more particularly adapted to be used in conjunction with safety devices for railroads, such as for instance described in a copending patent application filed by me October 30th, 1909, under Serial No. 525,413. As with 10 devices of this class, all circuits changers are conductively connected with each other and as the position of any one circuit changer depends upon that of the adjoining circuit changer and vice versa, it is 15 obvious that in case of an interruption of one of said connections, unintended movements of the circuit changers and of the safety devices controlled thereby may take place 20 which are apt to entail serious accidents.

25 The present invention overcomes all the above defects by providing means that prevent any undesired movements of the circuit changers after they have been set to a certain position, as more fully brought 30 out in the appended specification and claim.

In the accompanying drawing: Figure 1 is a diagrammatic view of a pair of coacting circuit changers embodying my invention, and Figs. 2, 3 and 4 are similar views 35 illustrating consecutive positions of the circuit changers.

The circuit changer A comprises essentially three vessels or tubes a, b, c which are jointly supported by a frame d. The latter 40 forms part of a tiltable armature f influenced by a pair of electromagnets g and h. Into the ends of tubes a, b, c are respectively sealed pairs of electric contacts which are adapted to be closed by the mercury 45 contained therein, the contacts temporarily closed depending upon the dip which said tubes assume. Tubes a and c are of less area in cross section than tube b, so that the mercury contained in tubes a and c will 50 require a considerably longer time to flow from one end of each tube to the other end thereof than is required by the mercury contained within tube b, after the dip of such tubes has been changed.

55 Into the right hand ends of tubes a, b are respectively sealed the contacts n and l,

while into the left hand ends of tubes a, c are sealed the contacts k and m. The contacts sealed into the right hand end of tube c and into the left hand end of tube b 60 are connected to other devices not shown in the drawings, such devices including the train protecting means proper.

In like manner, circuit changer A' comprises three tubes, a', b', c' carried by the 65 frame d' of a tiltable armature f', the diameter of tubes a', c' being considerably less than that of tube b'. Armature f' is adapted to be alternately attracted by the electromagnets g', h', the circuit changer 70 A' being in all respects a duplicate of circuit changer A. It is of course to be understood that the circuit changers A, A' are located a considerable distance apart according to the lengths of the safety zones 75 of the track which they are to protect. Into the right hand ends of tubes a', b' respectively are sealed contacts n', l', while into the left hand ends of tubes a', c' are sealed the contacts k', m', the contacts 80 shown at the left hand side of tube b' and at the right hand side of tube c' being connected to other devices not shown.

The electric current for operating the circuit changers is supplied through a pair of 85 feed wires +1 and -1 extending along the track and being connected to a suitable source of electricity (not shown), while the circuit changers are actuated by suitable circuit closers j adapted to be actuated by a 90 passing train or car, one of said circuit closers being shown in the drawings.

Main +1 is by wire 2 connected to circuit closer j which is in turn by wire 3 connected to contacts k, the latter being by wire 95 4 connected to electromagnet g, which is by wire 9 connected to the main -1. From main +1 leads another wire 5 to contacts l, which are in turn by wire 6 connected to contacts m, all of circuit changer A. From 100 contacts m, a wire 7 leads to the contacts n' of circuit changer A', which are by wire 8', electromagnet h' and wire 9' connected to main -1.

From main +1, there leads a wire 5' to 105 the contacts l' of circuit changer A', which are by wire 6', contacts m', wire 7', contacts n of circuit changer A, wire 8 and electromagnet h to wire 9. From wire 3 leads a wire 3' to contacts k' which are in turn by 110 wire 4' and electromagnet g' connected to wire 9'.

Upon the closing of circuit closer j , a circuit will be established, the current flowing from main $+1$ through wire 2 (Fig. 1), instrument j , wire 3', closed contacts k' , wire 4', electromagnet g' , and wire 9' to main -1 . Electromagnet g' will thus become energized to attract armature f' of circuit changer A', thereby reversing the position of said armature from that shown in Fig. 1 to that illustrated in Fig. 2. Owing to this rocking movement of armature f' , the liquid contained in tube b' will immediately flow to the other end of said tube to close contacts l' , while the liquid contained in tubes a' , c' will consume considerably longer time for performing the same function, so that the contacts m' and k' remain closed for a certain period after the tubes have assumed the oppositely inclined position (Fig. 2). In this way, a circuit is closed, the current flowing from main $+1$ through wire 5', closed contacts l' , wire 6', still closed contacts m' , wire 7', contacts n , wire 8, electromagnet h , and wire 9 to main -1 . Electromagnet h of circuit changer A will thus become energized to tilt armature f into the position illustrated in Fig. 3. In the meantime the liquid in tubes a' , c' of circuit changer A' has filled the lower right ends of said tubes, thereby opening the contacts l' , m' respectively. Shortly after the rocking of armature f of circuit changer A has been completed, the liquid contained in tubes a and c will also have flown into the lower left ends of said tubes, the parts thus assuming the position illustrated in Fig. 4. It is obvious that the effect above described could also be obtained if the conducting wires 7', 7 were directly connected to contacts l' , l without passing through contacts m' , m respectively. In this case however, it would not be possible to prevent the armature f' of circuit changer A' after having been tilted from being immediately returned to its previous position in case of an interruption of the current which serves for rocking the armature f of circuit changer A. Thus if wire 7' were broken, electromagnet h could not become energized, and armature f would remain in the position illustrated in Fig. 1, instead of being tilted into the position shown in Fig. 3 after armature f' has been tilted into the position illustrated in Figs. 2 and 3. Owing to the failure of armature f to leave the position shown in Fig. 1, a circuit would be established, the current flowing from main $+1$, through wire 5, still closed contacts l , wire 7 (which is now supposed to be directly connected to contacts l instead of being connected to contacts m), meanwhile closed contacts n' , wire 8', electromagnet h' , and wire 9' to main -1 . Electromagnet h' will thus

be energized to immediately return armature f' into its original position, thereby inviting accidents. By interpolating the contacts c' , c respectively, the armatures are secured against an immediate return to their previous position, as the circuits which cause the tilting of the armatures, are automatically interrupted immediately after such tilting has taken place. This is due to the fact that the contacts provided in the tubes of small diameter are broken shortly after the tilting movement of the corresponding armatures has been completed.

After the parts have assumed the position illustrated in Fig. 4, and have thus performed the work desired by closing certain circuits that actuate the train protecting devices, the armature f is first returned to its original position by a current that flows from main $+1$ through wire 2, circuit closer j , wire 3, contacts k , wire 4, electromagnet g , and wire 9 to main -1 . Electromagnet g will thus become energized to tilt armature f into the position illustrated in Fig. 1, thereby closing temporarily a second circuit, the current of which flows from main $+1$ through wire 5, already closed contacts l , wire 6, still closed contacts m , wire 7, closed contacts n' , wire 8', electromagnet h' , and wire 9' to main -1 . Electromagnet h' will thus become energized to tilt armature f' into the position shown in Fig. 1, thereby setting the device ready for the next operation.

I claim:

In a device of the character described, a pair of like circuit changers arranged at a distance from each other, each of said circuit changers comprising an electromagnetic device and a plurality of circuit closing means operable thereby, electric connections between said electromagnetic devices and circuit closing means, and means for sending electric energy through either of said electromagnetic devices, whereby the circuit closing means pertaining to the energized electromagnetic device are operated to close the circuit of the other electromagnetic device, said circuit including a selected number of circuit closing means of both of said circuit changers, one of which circuit closing means is closed for a limited period only, after the energizing of the first mentioned electromagnetic device.

In testimony whereof, I have signed my name to this specification in the presence of two subscribing witnesses.
